UNITED STATES PATENT OFFICE.

GEORGE H. BABCOCK, OF PLAINFIELD, NEW JERSEY.

DESIGN FOR A ROOFING-TILE.

SPECIFICATION forming part of Design No 20,404, dated December 16, 1890.

Application filed May 14, 1890. Serial No. 351,812. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawings, forming a part thereof.

- 10 The design relates to a clay or other tile having substantially a flat exposed surface, which, when assembled with other tiles of like surface, abut one another laterally and form a continuous surface; and said design consists 15 of a tile having for a surface ornamentation a Grecian border; and it also consists of a tile the exposed face of which is of rectangular form, having as a surface ornamentation a Grecian border.
- 20 In the accompanying illustrations, Figure 1 is a face view of a tile of the new design; and Fig. 2 illustrates a number of such tiles in an assembled condition, illustrating the effect of the surface ornamentation and the effect of

the latter in conjunction with the shape or 25 outline of the exposed face of the tiles.

The design relates particularly to the exposed or lower face of a tile, its upper portion partaking of various shapes.

As illustrated, the tile has diagonal upper 30 sides *a a*, which bear upper flanges. The lower or exposed portion of the tile is of rectangular form in outline with a plain surface *A*. The Grecian border is composed of a band *B* upon the plain surface of the tile and of 35 broken rectangular form, portions of the band lying contiguous with two edges *b d* of the tile. The surface of the band *B*, forming the Grecian border, may be a plain one, or may be ornamented in various ways, such as by 40 the series of convex heads *c*.

What is claimed is—

The design for a tile, substantially as described and shown.

GEO. H. BABCOCK.
